Primary Examiner — Ian Simmons*Assistant Examiner* — Dana L Sipos(74) *Attorney, Agent, or Firm* — Frijouf, Rust & Pyle, P.A.(57) **CLAIM**

The ornamental design for a fluid container, as shown and described.

DESCRIPTION

FIG. 1 is a top, front, right side perspective view of a fluid container showing our new design;

FIG. 2 is a top, rear, right side perspective view thereof;

FIG. 3 is affront elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is an elevation view of the closure portion of the fluid container shown at an enlarged scale;

FIG. 10 is an elevation view thereof, shown with the transparent shading removed for clarity; and,

FIG. 11 is a cross-section view taken along the line 11-11 in FIG. 9.
